[57] CLAIM

The ornamental design for a savings box toy, substantially as shown and described.

DESCRIPTION

FIG. 1 is a front elevational view of a savings box toy showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof;

FIG. 8 is a perspective view thereof in open condition; and

FIG. 9 is a perspective view thereof in open condition and in operation.

The broken lines on the drawing are for illustrative purposes only.
